UNITED STATES PATENT OFFICE.

LOUIS V. JOHNSON, OF ORANGE, TEXAS.

AIRCRAFT.

1,374,150.

Specification of Letters Patent. Patented Apr. 5, 1921.

Application filed July 3, 1919. Serial No. 308,464.

To all whom it may concern:

Be it known that I, LOUIS V. JOHNSON, a citizen of the United States, residing at Orange, in the county of Orange and State 5 of Texas, have invented certain new and useful Improvements in Aircraft, of which the following is a specification.

This invention relates to aeronautics, and more particularly to steering; and the ob-

10 ject of the same is to provide air craft with means additional to its vertical and horizontal rudders for correcting or for altering the position of the craft within the air. On water craft the order "trim ship" is 15 given when the boat is not traveling on an even keel, or in other words when there is a list to starboard or to port, but the ship is "trimmed" fore and aft by the proper disposition of the cargo when it is loaded.

20 In an air craft the position of the body can be corrected by this invention and then steered by the rudders, or the invention may be used to assist in steering. Specifically, the invention consists in providing the body 25 with a weight, such as a car which may carry cargo or passengers, mounting the weight so that it may be moved with respect to the center of mass, and equipping the structure with a control standing within 30 reach of the driver or pilot so that he can adjust the weight at any time. Details of the preferred manner of carrying out this invention are set forth below and shown in the drawings wherein:

35 Figure 1 is a side elevation of an aeroplane equipped with this invention.

Fig. 2 is a plan view thereof with the plane omitted.

Fig. 3 is a front elevation.

40 Fig. 4 is a sectional detail illustrative of the control levers for the rudders, this view showing the movable car, the control therefor, and the connection between this control and the car itself.

45 The framework of this craft, broadly designated by the numeral 1, need not be of special structure, as far as the present invention is concerned, but is shown herein as carrying a body 2 which is sharp at the 50 front and rear ends and is provided with a floor 3, and at the top of the framework is a single plane 4 arched transversely, as seen in Fig. 3. The craft illustrated is driven by a forward propeller 5 and a rearward propeller 6, each having its own motor 7, although this is not essential. It is desir-

able, however, that heavy units such as the propellers and the motors shall be so placed that the center of mass of the entire structure shall be at a point which in Fig. 1 60 would probably be about midway between the uprights of the framework, and when the craft is propelled straight through the air and on an even keel, the floor 3 will be 65 level. The numeral 8 designates the horizontal rudder and the numeral 9 the vertical rudder, these being operated by suitable connections between them and the control levers 18 and 19 shown in Fig. 4 as within 70 reach of the driver or pilot when he sits on his fixed seat 10. Details are not important, excepting that as usual he manipulates one lever to adjust the position of the horizontal rudder 8 for varying the pitch of the craft and eventually its altitude, and he manipulates the other lever for adjusting the vertical rudder 9 for steering the craft to either 75 side.

The gist of the invention lies in the provision of a weight which is herein shown 80 as a car 11 having wheels 12 mounted on tracks 13 upon the floor 3 entirely in rear of the operator's seat 10, the tracks 13 leading in both directions past the center of mass. As herein shown, these tracks run 85 fore and aft, and the adjustment of the car would therefore be longitudinal of the body 2 along its transverse center, but the broadest latitude in this respect is reserved. The car is herein shown as provided with seats 90 14 which may accommodate passengers, but they could be omitted and the car could carry freight. Also it might be slidably mounted on suitable guides instead of having wheels traveling on rails. It is essential 95 only that the movable element be heavy so that it may be described by the word "weight," and that it may rest exactly at the center of mass or may be adjusted away from said point.

One means of adjustment is shown in Fig. 4. It consists of an endless cable 15 attached at 16 to the car and its rear end passing over an idler 17, while its front end passes around a pulley fast on the shaft of 105 a manual control which is herein shown as a wheel 19 mounted within reach of the pilot when he is on his fixed seat 10. By turning this wheel one way or the other the car may be adjusted forward or backward, 110 as will be clear. As illustrated in Fig. 4, the wheel 19 which moves about a horizon-

tal pivot is provided with a plurality of peripheral notches 31 adapted to receive the forward end of a pawl 32 pivoted intermediate its ends to the frame, as indicated at 33. 5 By moving the pawl out of engagement with the wheel 19, the shaft carrying the wheel may be operated for imparting longitudinal movement to the ballast carriage 11.

Another detail which is employed in this 10 machine is that, instead of using landing wheels, I prefer the use of legs 20 and 21 pivoted at 22 beneath the floor 3 of the body, and each leg having a foot 23 at its lower end extending rearward at about right angles to the leg itself. The pivots are 15 preferably in the shape of knuckle joints so that the legs may not move farther forward than to the position shown in Fig. 1, but they may move backward as indicated in dotted 20 lines, and they do so move when the craft starts off. By preference the front leg or legs are longer than the rear leg or legs so that the plane 4 shall incline upward and forward at starting, the better to catch the 25 air and cause it to rise before sufficient momentum has been attained.

With the air craft equipped with this invention it is clearly obvious that the pilot, by adjusting the weight forward, can 30 depress the bow or by adjusting it rearward can raise the bow, and thus descend or ascend to some extent without using the horizontal rudder 8 at all. He may increase the pitch by using this rudder, or he may use 35 the rudder first and then increase the pitch by moving the weight. If the latter be mounted on a track 13 extending along the transverse center of the floor, it is obvious that adjustment fore and aft will have no 40 effect on lateral steering by means of the vertical rudder 9, but it is conceivable that the weight might be mounted on tracks transverse to the body, or it is possible that it could be mounted for transverse movement 45 on a platform which itself is movable longitudinally, and suitable controls provided for adjusting the weight in either direction. It is desirable, however, that the weight in its normal or usual position shall 50 stand at the center of mass, perhaps midway between the two motors and the propellers and about beneath the center of the plane or planes, whatever their number and construction. If so, then the adjustment 55 of the weight in any direction from such

point will naturally depress that part of the structure toward which the weight is moved, and such depression may be employed by the pilot for steering purposes or to assist in steering.

Attention is invited to the transverse arch of the plane, as shown in Fig. 3, the plane being of preferably the same curvature throughout its entire length. This construction is purposely adopted to afford an 65 element of safety which is important, because a craft equipped with one or more planes so made will glide to earth safely, even if the motors should fail entirely. Moreover, this construction is highly desirable 70 because it facilitates rapid flying because the curved or arched planes cut edge-wise through the air, and so the plane need be tilted only slightly out of the horizontal to affect the pitch considerably. Finally, in 75 case of accident, and if the machine were dropping straight to earth, an arched plane of this kind would trap air and serve, to an extent, in the capacity of a parachute.

Having thus described the invention, what 80 is claimed as new is:

In an air craft, the combination with a transversely bowed sustaining plane, of a main body carried by and arranged beneath said plane and disposed completely within 85 the lines of the same, a fixed pilot seat arranged in the forward portion of the body, a track carried by the said main body and extending longitudinally of the same, a passenger body mounted upon said track and 90 movable longitudinally within the first named body rearwardly of the fixed pilot seat and provided with a plurality of passenger seats disposed in the longitudinal plane of the pilot seat, a flexible element 95 connected to the ends of the passenger body, guides supporting said flexible element and disposed adjacent the ends of the main body, and means arranged adjacent the pilot seat and connection to said flexible element 100 whereby the pilot may shift said passenger body and the passengers within the same longitudinally of the main body without leaving the pilot seat, said passenger body and the controlling means for the same being disposed entirely within the lines of 105 and housed by the main body.

In testimony whereof I affix my signature.

LOUIS V. JOHNSON. [L.S.]
